UNITED STATES PATENT OFFICE

LEONARD L. RUGGLES, OF WHEATON, ILLINOIS, ASSIGNOR TO RESERVE HOLDING COMPANY, OF KANSAS CITY, MISSOURI, A CORPORATION OF DELAWARE

TELEPHONE SYSTEM

Application filed December 2, 1927, Serial No. 237,140. Renewed May 5, 1930.

The present invention relates to telephone systems in general; but is concerned more particularly with semi-automatic telephone systems of the remote controlled type, and especially with semi-automatic magneto exchanges.

In my application, Serial No. 199,917, filed June 20, 1927, there is disclosed a semi-automatic telephone system of the above type. In this prior system, the initiation of a call is effected responsive to the operation of the hand generator at a calling station, and the clearing out of the connection after it has been set up by the semi-automatic operator through the automatic switches is accomplished when ringing current is transmitted by the usual ringing-off operation. In this way, the subscriber's lines are operated in exactly the same manner as though they are receiving purely manual service, and no operating or holding currents are employed, with the result that the bad effects of leaking currents due to faulty insulation, such as is met with when automatic service is applied to long rural lines, is not encountered. In the present disclosure, however, this arrangement has been modified to the extent that only the initiation of the call is dependent upon ringing current from the calling station, a slight holding current being provided from the exchange over the calling line to hold the connection under the control of the calling station after the connection has been set up. It is accordingly an object of the invention to provide suitable holding circuits such that the tying up of equipment due to faulty insulation will be minimized. By this method of releasing the connections, the difficulty encountered in the above-mentioned prior system due to the frequent failure of subscribers to "ring off" has been obviated.

A feature of the invention lies in the arrangement whereby holding current is supplied over one conductor of the calling line through the calling station and back to the exchange over the other conductor of the calling line to the holding relay in the exchange, so that an accidental ground connection will not cause a connection to be held

up, as would be the case if the holding current were supplied through a holding relay to the line at the exchange.

Another object of the invention is the production of new and improved circuit arrangements at the switchboard of the controlling operator in the operating center whereby she can handle the calls more readily and with less labor per call. This improvement consists, in general, in substituting key-controlled locking and slow acting relays to perform and time switching functions automatically which were heretofore performed and timed by keys.

A further object of the invention is in the production of new and improved circuit arrangements whereby a supervisory switch is provided individual to the single operating trunk connecting the operating center with the semi-automatic exchange. This supervising switch may be operated at the will of the operator to extend a connection to any one of the connectors in the semi-automatic exchange, or directly to any of the semi-automatic lines. A feature of the invention lies in the arrangement whereby the supervising switch is brought into play responsive to the projection of ringing current over the operating trunk and responsive to certain abnormal conditions in the semi-automatic exchange, remaining inactive at all other times.

A further object of the invention is to provide suitable circuits whereby the relay-type finder used in the prior system is replaced by a mechanical step-by-step rotary-type finder in order to simplify the equipment.

A further object of the invention is in the provision of suitable arrangements whereby the operator can unbalance the operating trunk in order to perform various special operations in the semi-automatic exchange. One special operation is the release of any partly-set-up connection in case the operator discovers that she has made a mistake. Another special operation is the release of any connector to which the operator has extended a connection during the supervising operation, and still another special operation is the application of ringing current to any line

to which the operator has extended a connection through the supervising switch.

There are other objects and features having to do, for the most part, with the various details involved in carrying out the objects set forth above. The various objects and features of the invention will be understood better upon a further perusal of the specification in connection with the accompanying drawings comprising, Figs. 1-3. Referring now to the drawings, they show by means of the usual circuit diagrams a sufficient amount of equipment in a telephone system embodying the features of the invention to enable the invention to be understood.

Fig. 1, shows certain equipment at the controlling position at an operating center. From this position, the switches in several small semi-automatic exchanges may be controlled. This drawing shows also an operating trunk connecting the trunk circuit TC1 with the semi-automatic exchange containing the equipment shown in Fig. 1 to the right of the operating trunk, and in Figs. 2 and 3. A trunk circuit such as the trunk circuit TC1 and an operating trunk is provided for each of the semi-automatic exchanges. These trunk circuits may be all at one position unless there is more traffic than one operator can handle, in which case two or more controlling positions may be provided.

Fig. 2, shows the trunk circuit TC2 terminating the semi-automatic exchange end of the operating trunk and having associated therewith the finder F and the supervising switch S.

Fig. 3, shows the connector C and a portion of the associated master switch, as well as the line switch of the line of sub-station A and the line of sub-station B. This connector is one of a group of ten, for example, provided to handle the local calls. The toll connections between the semi-automatic exchange and other exchanges are handled by a toll operator in the semi-automatic exchange over toll lines (not shown) by suitable toll switches having their banks connected in multiple with the bank of connector C and the other local connectors. Since the toll equipment forms no part of the present invention it has not been shown herein. This equipment, however, may be more or less similar to the toll equipment shown in the above-mentioned prior application, except that it may be very much simplified owing to the fact that the supervising operations in the present disclosures are taken care of by the supervising switch SS, Fig. 2, instead of over the toll lines and through the toll connectors as in the prior application.

The connector C Fig. 3, and the supervising switch SS Fig. 2 are each of the usual vertical and rotary type, having back contacts arranged in ten horizontal levels of ten contact sets per level. The code machine in-

dicated in Fig. 3 contains the contacts shown, which may be operated by any well known or desired type of cam arrangement. The cam device causes the contacts to deliver the desired distinctive codes to the various conductors extending to the bank of the code switch and to the banks of the other code switches in multiple, the pick up conductor being grounded momentarily before the starting point of the codes is reached and the stop conductor being grounded momentarily after all the codes have been transmitted.

The apparatus having been described in general, a detailed description of its operation will now be given. For this purpose it will be assumed that the subscriber in sub-station A desires to converse with a subscriber at sub-station B.

Call from sub-station A to sub-station B

After removing his receiver, the subscriber at sub-station A operates the push button on his telephone connected in the generator bridge so as to condition the line circuit for signalling the operator, as in modern magneto practice. The operation of this push button results in the disconnection of the generator from the usual bridge and in the grounding of one terminal. The result is that the ringing current is transmitted from ground over the lower talking conductor only and it operates the line relay 302 of the lineswitch LS, whose upper winding is connected between the lower talking conductor and ground through the cut-off contacts 303. Upon operating, line relay 302 locks itself at its lower contacts to ground through contacts 306 in a circuit including its lower winding, and at its upper contacts it closes a circuit for the pull-down winding 304 of the lineswitch, which circuit includes the open main conductor 361. Responsive to the closure of the circuits through the pull-down winding 304, the pull down armature 307 is operated to complete the connection to the preselected connector C, and the cut off contacts 303 are opened by the associated armature to disconnect the upper winding of relay 302 from line. When the plunger (not shown) is operated by the pull-down armature 307, and the contacts are forced into engagement to complete the circuit, the ground potential on release trunk conductor 316 of the connector C, through upper winding of relay 321 and off-normal 328, is placed on the private-normal conductor 301 of the lineswitch to make the calling line busy in the banks of the connectors and to close a circuit through the cut-off and holding winding 305. The current flow through this winding is sufficient to maintain the line-switch in an operated position. Just as the armature 307 completes its stroke, it separates the contacts 306, opening the locking circuit of line relay 302, whereupon relay 130

302 falls back and opens the circuit through the pull-down winding 304. As a further result of the operation of the lineswitch, ground is placed at the contacts thereof on the holding conductor 317, causing the master switch, under the control of its start relay 367, to advance and preset another trunk line. As a further result of the grounding of conductor 317, a locking circuit is prepared for the lower winding of relay 321, which relay operates through its upper winding in series with the cut-off winding 305 of the line-switch LS and closes the locking circuit at its inner lower contacts. As a further result of the operation of relay 321, it removes ground from release conductor 274 and places ground on holding conductor 343, so as to prepare the switch for operation, and at its upper armature it grounds the finder-start conductor 271, at the same time carrying the stopping, ground potential from the common grounded conductor 278, through the upper contacts of relay 323, through its middle upper contacts to the stop conductor 276 in the bank of the finder F, Fig. 2.

As a result of the placing of the ground potential on start conductor 271, a circuit is closed through contacts of relays 202 and 201, Fig. 2, for the operating magnet 208 of the finder F. When the operating magnet responds, it prepares the wipers for advance by the usual operation and closes a circuit for stepping relay 201. Stepping relay 201 operates and opens the circuit of operating magnet 208, whereupon magnet 208 falls back and advances its wipers 209-213 one step, at the same time opening the circuit of relay 201. This stepping operation continues until stop relay 202 is pulled up through the upper contacts of relay 206 and through the test wiper 213 when the latter encounters the grounded stop conductor 276 coming from the connector C.

When relay 202 operates, it opens the circuit of operating magnet 208 at its lower armature, stopping the operation of the finder. At its middle lower armature and at its upper armature, relay 202 connects the incoming talking conductors to wipers 209 and 210 of the finder, and at its inner armature it connects the operating conductors from the inner left hand terminals of the repeating coil R-2 to the line relay 204 through the differential relay 203, thereby placing a battery potential on the operating trunk through the said line relay and differential relay. When this occurs, line relay 103, Fig. 1, at the operating center operates through contacts of relays 102 and 104 and over the operating trunk through the right hand windings of the repeating coil R1. Upon operating, relay 103 closes a circuit for the call lamp at the operator's switchboard in order to indicate that a call is waiting. At the same time,

relay 204, Fig. 2, operates over the operating trunk, but the differential relay 203 does not operate at this time due to the fact that the current flow is balanced in its two windings. Relay 204, upon operating, closes a circuit for relay 205, which relay operates and closes a circuit for relay 206. Relay 205 closes a local circuit for stop relay 202 and relay 206 disconnects the stop relay from wiper 213. Relay 205 also prepares an operating circuit over wiper 212 to conductor 275, extending to the connector C.

Upon noting the lighted condition of the call lamp associated with the trunk circuit TC1, the operator responds by momentarily operating her answering key ANS. When this is done a circuit is closed for relays 102 and 106 in multiple with the call lamp, whereupon these relays operate and lock themselves to ground through contacts of slow acting relay 105. Relay 102 closes at its inner upper contacts a circuit for the busy lamp through contacts of relay 104, whereupon the busy lamp becomes lighted. As a further result of the operation of relay 102, it disconnects the incoming operating leads from line relay 103 and connects them to ground through the impulse contacts of the calling device, the lower operating conductor being extended through contacts of the special-release key associated with the calling device. As a result of this operation, the line relay 103 falls back and extinguishes the call lamp. Relay 106 which is operated in multiple with relay 102, prepares a circuit for relay 105 at its inner upper contacts, at the same time connecting up the operator's headset conductors to the talking circuit at its upper and lower contacts. The operator may now converse with the calling subscriber over the talking circuit outlined by the heavy conductors.

Upon learning the destination of the call, the operator proceeds to dial the digits of the number by means of her calling device. Since the line of substation B terminates in the first level of the bank of the connector C, the first digit dialled is the digit 1, one interruption being produced by the impulse springs of the calling device when this digit is dialled. When this interruption is produced, the line relay 204 of the trunk circuit TC2 is caused to fall back one step momentarily, closing a circuit through contacts of relay 205, wiper 212, conductor 275, off-normal contacts including spring 329, and the series relay 322, for the vertical magnet 323 of the connector C. The vertical magnet responds by raising the wiper 336-338 opposite the first level of bank contact. The slow-acting relay 322 responds and maintains its own circuit and that of the vertical magnet intact after the off-normal contacts have shifted, as they do upon the first vertical step. At the end of the vertical movement, relay 322 falls back and

shifts the operating circuit from the vertical magnet to the rotary magnet 334.

When the operator dials the second digit in the number, the impulses are transmitted to the rotary magnet 334 of the connector C through contacts of relays 322, 323, and 325. The rotary magnet 334 responds by rotating the wipers 336—338 into engagement with the bank contacts in which the line of sub-station A terminates. Slow-acting relay 324 is energized in multiple with magnet 334 throughout the rotary operation. At its upper armature, relay 324 disconnects test wiper 337 from the test winding of relay 323 and connects it instead through contacts of relay 325 to the winding of busy relay 323, and at its lower contact it shunts the corresponding contacts on relay 323 and the circuit of the rotary magnet so as to maintain its own circuit and that of rotary magnet 334 intact in case busy relay 323 energizes through test wiper 337 during the rotary movement.

From this point the operation depends upon whether the line of sub-station B is busy or idle when the call is made. Assuming first that the line is busy, busy relay 323 is energized, when the wipers come to rest, through a ground potential on the test contact encountered by test wiper 337. In this case, when relay 324 falls back it completes at the normally-closed contacts controlled by its upper armature, a circuit through the inner upper armature of relay 323 for locking relay 323 to the locking conductor 343. With relay 324 deenergized and with relay 323 operated, the operating circuit is opened at the inner lower contacts of relay 323. At the lower contacts of relay 323 the busy-tone current is placed on the calling line from the common busy-tone conductor 365 through contacts of relay 325. Upon hearing the tone produced by the flow of current, the calling subscriber is expected to replace his receiver and call later.

Assuming now that the line of sub-station B is idle when called, busy relay 323 is not operated when the wipers land on the contacts of the called line and switching relay 325 operates upon the falling back of slow acting relay 324 to seize the called line. Relay 325 operates through its lower winding, whose lower terminal is connected to the grounded conductor 343 through contacts of busy relay 323, and whose upper terminal is connected to test wiper 337 through contacts of relay 324. The circuit to battery is completed over the private normal conductor through the cut-off winding of the lineswitch on the called line, which winding corresponds to winding 305 of the lineswitch LS. This cut-off winding energizes sufficiently to disconnect the line relay, but not sufficiently to operate the lineswitch. Upon operating, relay 325 closes a locking circuit for its upper

winding to the grounded conductor 343 at its inner upper contacts; at its middle upper contacts it places ground directly on wiper 337, thereby supplying a more direct guarding potential to the test conductor of the called line; at its inner lower contacts it transfers the operating circuit from the rotary magnet 334 to the operating magnet 341 of the code switch; it opens a point in the circuit of busy relay 323 at a pair of upper contacts; grounds the negative talking wiper 336 at its upper contact to afford a return path for the ringing current; opens a point at its lower contacts in the busy tone circuit and prepares a ring-back-tone circuit through condensers 335; and at its middle lower armature it closes a point in the energizing circuit of pick-up relay 326.

When the operator dials the stations digit in the desired number, the impulses of current are transmitted to the operating magnet 341 of the code switch. When the operating magnet 341 responds, it sets the wiper 342 on the bank contact corresponding to the code assigned to the called station B. Slow-acting relay 324 is energized throughout the code digit and it maintains the circuit of busy relay 323 open after off-normal contacts 339 of the code switch have closed.

At the end of the code digit, relay 324 falls back and closes a circuit for operating the busy relay 323, whereupon relay 323 operates and closes a further point in the circuit of pick-up relay 326, at the same time opening the operating circuit at its inner lower contacts to prevent further movement of the code switch.

When the pick up conductor 364 is grounded by the code machine prior to the beginning of the code period, a circuit is closed through contacts of relay 323 and 325 for pick-up relay 326, whereupon pick-up relay 326 operates and locks itself to conductor 343 in the usual manner. Pick-up relay 326 also prepares a circuit for stop relay 327 at its inner contacts and at its lower contact it connects wiper 342 of the code switch to the positive wiper 338 so as to afford a path for transmitting the ringing current to the called line. As a result, the code selected by the code switch is now transmitted over the called line and operates the various ringers on the line, the small condenser 335 permits a small amount of ringing current to reach the calling line through contacts of relays 323 and 325 so that the calling subscriber is notified of the signalling operation.

After the code has been transmitted, the stop conductor 366 is grounded by the code machine, closing a circuit through contacts of relay 326 for stop relay 327. Relay 327 operates and locks itself to conductor 343, at the same time opening the ringing circuit and completing the talking circuit at its upper and lower armatures.

As soon as the subscriber at sub-station B responds to the ringing of his bell by removing his receiver the two subscribers may converse with each other in the usual manner.

- 5 After having dialled all the digits in the number, the operator frees her common equipment from the operating trunk at the trunk circuit TC1 by momentarily depressing the release key RLSE. When the release key 10 is operated, it closes a circuit through contacts of relay 101 for the upper winding of relay 104. It will be noted that this circuit is taken through contacts of slow-acting relay 101, which is operated through off-normal contacts of the calling device as long as the calling device is off-normal and for a short time thereafter so as to prevent premature release in case the operator should operate her release key during or too soon after the 20 last return to normal of the calling device. When relay 104 operates it closes a circuit in parallel with its upper winding through contacts of the locked-up relay 106 for the slow-acting relay 105. Relay 105 operates 25 and closes a locking circuit for the lower winding of relay 104 through the inner lower contacts of relay 104, at the same time opening the locking circuits of relays 102 and 106. Relays 102 and 106 now fall back and disconnect the operator's head set and the calling device from the trunk circuit. Relay 106 also 30 opens the circuit of the slow acting relay 105 so as to start the release of this relay right away regardless of whether the operator permits the release key to restore immediately or not. It will be noted that relay 104 at its upper and lower contacts opens both operating conductors so that relay 103 is not re-operated when relay 102 restores. When relay 105 35 falls back it opens the locking circuit of the lower winding of relay 104, with the result that relay 104 now falls back and reconnects relay 103 to the operating conductors providing the operator has permitted the release key 40 to restore. In case the operator still has the release key operated, relay 104 merely remains operated and keeps the operating conductors open until the release key is permitted to restore. The slow acting relay 105 is designed so that it requires a sufficient time to 45 fall back in order to permit the clearing out operation to be hereinafter described to take place in the trunk circuit TC2, Fig. 2.

Referring now to Fig. 2, when line relay 50 204 falls back responsive to the foregoing opening of the operating circuit at the upper and lower contacts of relay 104, Fig. 2, it again places ground on the operating conductor 275 through wiper 212, but this does 55 not result in further operation of the code switch, Fig. 3, because relay 323 has the operating circuit open at this time at its inner lower contacts. A moment later, the slow acting relay 205 falls back and opens the 60 operating circuit at its lower armature, at

the same time opening the circuit of slow acting relay 206 and the circuit of relay 202. Relay 206 is rendered slow acting so as to allow relay 202 to fall back and permit the finder to advance to a different position in 70 case another call is waiting, regardless of whether or not the connector C, Fig. 3, has ungrounded its stop conductor 276 at the upper contacts of relay 323. If another call is waiting, start conductor 271 is grounded and operating magnet 208, under the control of relay 201, starts advancing the finder again. Slow-acting relay 206, however, is arranged to be only slightly slow, so that it falls back almost immediately and reconnects stop wiper 213 to stop relay 202 so as to enable the finder to stop on the next contact set in case the next connector is one on which the call is waiting. If, on the other hand, no call is waiting, the finder F does not 80 move at this time but stands on the connector last used until another call comes in.

Referring again to the established connection it will be noted that a multiple holding bridge is established over the called line so 90 that the connector C will remain operated until both subscribers replace their receivers. If desired, talking condensers could be inserted between the line wipers 336 and 338, and the point in the talking connection to 95 which the impedance coil 319 and holding relay 320 are connected.

When both subscribers have replaced their receivers, the current flow through impedance coil 319 and relay 320 ceases, and relay 100 320 falls back, removing ground from release trunk conductor 316. When this occurs, the cut-off winding 305 of the lineswitch LS de-energizes and permits the line switch to restore. When the line switch restores, the 105 ground potential is removed from holding conductor 317, rendering the connector idle again in the bank of the master switch and unlocking release relay 321 of the connector. Relay 321 now falls back and at its inner upper armature it disconnects ground from holding conductor 343 and places ground on conductor 274. When ground is removed from conductor 343, the locked-up relays 325, 326, and 327 fall back. The release magnet 332 now operates through off-normal contacts 330 from grounded conductor 274 and restores the connector to normal, and release magnet 340 of the code switch operates through the middle upper contacts of relay 110 323 and restores the code switch to normal, whereupon the off-normal contacts 339 of the code switch open the circuit of relay 323, permitting relay 323 to fall back and open the circuit of release magnet 340. The circuit 115 of release magnet 332 is opened at off-normal contacts 330.

The connection is now released and the apparatus involved therein is in condition for further use.

Release after an error

Assuming now that the operator at the operating center is setting the connector C and discovers that she has dialled a number other than that called for by the calling subscriber, she may release the connector C without releasing the calling line switch, the line switch LS for example, by operating the special-release key, Fig. 1, associated with the calling device. When this release key is thrown, the lower operating conductor is opened, whereupon current ceases to flow through the lower winding of differential relay 203, Fig. 2, line relay 204 being maintained operated over the upper operating conductor. Relay 203 now operates and places ground at its lower contacts on release wiper 211, extending ground over conductor 274 to the release magnet 332 by way of off-normal contacts 330 and to release magnet 340 of the code switch by way of the middle upper contacts of relay 323, in case the code switch has been operated. This restores the connector to normal mechanically, without removing ground from conductor 316 to permit the calling line to switch to release. At the contacts of the release magnet, the ground potential is removed from conductor 343 so as to permit any locked-up relays to be restored. When the operator has held the special-release key operated long enough to permit the releasing operation to be completed, she restores the key, whereupon the differential relay 203, Fig. 4, falls back again and removes ground from the release conductor 274.

Master-switch protection

In order to prevent the master switch from operating unnecessarily in case all of the connectors have been seized, the guard relay 368 is provided to disconnect the start relay 367 and to prevent operation of further line switches by removing battery from the common operating conductor 361. This relay is normally energized by ground potential supplied by each of the connectors, ground potential being supplied to conductor 363 by the connector C through contacts of relays 321 and 327. Relay 321 it will be recalled energizes as soon as the connector is seized. Now, as soon as the last connector is seized, the relay corresponding to relay 321 removes ground at the last point from conductor 363, permitting stop relay 368 to fall back and render the master switch inoperative until a connector becomes idle, at which time ground is restored to conductor 363.

All-trunks-busy signalling

Arrangements have been made for signalling the operator in case all trunks accessible to the line switches and extending to the connectors become busy, as some of these connectors may be indicating busy when, as a

matter of fact, they are not being used any longer. They may be held up due to poor line insulation or to subscribers having neglected to replace their receivers after conversation. It is obviously undesirable to signal the operator that all trunks are busy as soon as the last connector has been taken for use because the signalling operation would interfere with the handling of the last call. Furthermore, a connector may become idle and be released before the call has been taken care of. At any rate, the apparatus for signalling the operator that all trunks are busy does not come into play until the last connector has been operated.

Assuming now, that all connectors are busy except the connector C and that the connector C is seized by the lineswitch LS in the heretofore described manner, the master-switch-stop relay 368 falls back as soon as relay 321 operates upon the seizure of the switch. Then, when the operator has responded to the call and has operated the connector, ground is removed at the last point from conductor 277 when pick up relay 326 operates after the connector C and the associated code switch have been set. When ground is so removed from conductor 277, the all-trunks-busy relay 232, Fig. 2, falls back and, at its lower armature, grounds wiper 245 of the supervising switch, at the same time at its inner lower armature placing a busy tone on the upper wiper 243 of the supervising switch through contacts of the alarm relay 233. Relay 232 also, at its inner upper armature, closes a circuit for the upper winding of signal relay 234. Relay 234 operates and locks itself to ground through contacts of off-normal relay 231, at its inner upper contacts. At its upper armature, relay 234 opens a point in the circuit of the associated release magnet; at its inner lower armature it places ground on start conductor 271; and at its middle lower armature it grounds the test conductor extending to the bank of the finder F and representing the supervisory switch SS. The finder F now operates to find from which point the call is coming and continues to rotate until it stops on the contacts associated with the supervisory switch, these being the last contacts in the bank. When this occurs, stop relay 202 operates through stop wiper 213 and through contacts of relay 231 and the operated relay 234, and stops the operation of the finder. Relay 202 also connects up the operating conductors at its inner contact, thereby signalling the operator in the usual manner.

When the operator responds, she hears, through the wipers 209 and 210 of the finder F, the busy tone placed on the wipers of the supervisory switch SS. The presence of this busy tone on the operating trunk indicates to the operator that all trunks are busy, and

she proceeds to supervise the connectors and find out which, if any, are operated and not in use.

Upon hearing the busy tone on the operating trunk, the operator dials the digit 9 and proceeds to supervise the various connectors.

When the digit 9 is dialled, the nine impulses of current transmitted by line relay 10 204 are received by vertical magnet 241 of the supervising switch SS through wiper 212, on its last contact, and the off-normal contacts 238 and series relay 235. Vertical magnet 241 responds by raising the wipers 15 243—245 opposite the ninth level of bank contacts. Due to the combined action of off-normal contacts 238 and 239, and slow-acting series relay 235, the operating conductor is maintained in connection with the vertical 20 magnet until the end of the vertical movement, whereupon it is transferred to rotary magnet 242. Upon the closure of off-normal contacts 237, off-normal relay 231 operates and ungrounds the start conductor and the 25 associated step conductor at its middle lower and lower armatures, respectively, and at its inner lower armature it reoperates relay 232 so as to remove the busy-tone connections from the talking conductors.

Having dialled the digit 9, the operator 30 now dials the digit 1, whereupon the wipers are advanced one step by rotary magnet 242 to make connection with the first connector, it being assumed that there are ten connectors or less. It will be noted that the first 35 set of bank contacts in the ninth level are connected to the talking conductors 272 and 273 extending to the connector C. Accordingly, the operator is enabled to listen to the 40 conversation in case there is one involving this connector.

Assuming that the operator, upon listening in, discovers that there is no conversation being carried on over this connector, 45 she releases the connector by throwing her special-release key, unbalancing the differential relay 203. Differential relay 203 responds by grounding wiper 245. The ground potential placed on this wiper is transmitted 50 to the lower conductor 318 of the trunk line extending to the connector C, shunting the holding relay 320, whereupon this relay falls back and permits the connector to release in the heretofore-described manner.

55 In order to supervise the next connector, the operator again dials the digit 1, whereupon the switch SS is advanced another step.

After having supervised all the connectors, the operator frees her operating trunk 60 by manipulating her release key with the heretofore described results. In this case, in addition, the falling back of relay 206 results in the ungrounding of locking conductor 247, off-normal relay 231 being op-

erated through off normal contacts 237 of this time. When conductor 247 is ungrounded, relay 234 falls back and closes at its upper armature a circuit for the release magnet through contacts of the off-normal relay, whereupon the supervising switch is restored to normal in the usual manner.

Upon hearing the busy tone on the operating trunk, the operator dials the digit 9 and proceeds to supervise the various connectors.

In case the operator found all of the connectors being used, she of course has not released any of them, and the all-trunks-busy condition continues after she has cleared out her equipment. In this case, relay 232 falls back and again operates 234 whereupon the operator is again signalled. The operator may ignore this signal for an interval in this case and wait awhile before again supervising the connectors.

Supervising alarm signals

In any exchange there is provided a number of alarm signals to indicate when abnormal conditions exist, such as the blowing of fuses or the operation of heat coils on the main frame. Arrangements have been made in this case to use the same supervising switch SS, Fig. 2, to supervise alarms. For the purpose of illustrating how this is done, a heat coil 255 has been shown within the dotted rectangle labelled "alarm circuit". When an abnormal current flow occurs in the associated line, the heat coil is permitted to turn due to the melted solder within the heat coil, permitting contacts 253 and 254 to close.

Assuming now that the heat coil 255 has 95 operated and permitted the contacts 253 and 254 to close, contacts 254 prepare a signalling circuit from the ringing lead through the reducing condenser 255 to the associated contact in the tenth level of the bank of wiper 243. Contacts 253 extend a ground 100 potential through contacts of relay 251 to conductor 246, and closing a circuit through contacts of off-normal relay 231 for the alarm-start relay 233. Relay 233 operates 105 and closes a circuit for relay 234 in order to cause the finder F to advance to the supervising position, at the same time placing ground on wiper 245 and a ringing tone on wiper 243. Responsive to the operation of 110 relay 234 the finder F advances to supervising position in the heretofore described manner and the operator, upon responding 115 hears the ringing tone placed on by relay 233 and knows that an alarm condition exists.

In order to determine just what alarm condition exists, the operator dials the digit 0 and then proceeds to operate the supervising switch step by step across the tenth-level contacts. When the off-normal relay 231 operates, relay 233 is disconnected and falls 125 back to clear the talking conductors.

As soon as the first contact in the set is reached by wipers 243—245, the ground potential placed on wiper 244 through the contacts of relays 234 and 236 passes through the 130

bank contact on which wiper 244 is standing and operates relay 251, which closes a locking circuit for itself through contacts 253, removing ground from conductor 246. The 5 operator now hears the ringing-current-tone and impressed on the operating trunk through the tenth-level contact in the bank of wiper 243. She then makes a note of the particular alarm condition which exists. 10 Since two alarm conditions may exist simultaneously, the operator proceeds to operate the connector over the various other alarm contact sets so as to be sure that she has noted all alarm conditions, as some are 15 more important than others and would call for a more prompt action on the part of the person assigned to alleviate the trouble. The operator will hear a ringing-current tone on each alarm number at which the associated 20 alarm device is in an operated position.

The supervising switch SS is released in this case in the hereinbefore-described manner. When the release position is reached, off-normal relay 231 falls back and again connects relay 233 to conductor 246 but conductor 246 has been ungrounded by the above-mentioned operation of relay 251, with the result that the alarm condition does not again display on the operating trunk until 25 the trouble has been cleared and another alarm condition has occurred.

Calling subscribers' lines through the supervising switch

35 The operator may at one time or another have occasion to call one of the lines over the operating trunk so that she herself may get into communication with a certain subscriber. Assuming that the operator wishes 40 to do this, she operates the ringing key connected in the operating trunk just to the right of the repeating coil R-1, projecting ringing current out over the operating trunk. When this is done the ringing current is repeated through the repeating coil R-2 and passes through contacts of relay 202 to the 45 lower winding of the ring-up relay 234 of the supervising switch SS. Relay 234 operates and locks itself to conductor 247, whereupon the finder F is caused to operate and extend a connection to the supervising switch in the hereinbefore described manner.

When the upper armature of relay 234 grounds the conductor extending to wipers 50 244, relay 233 operates through contacts of relays 231 and 232 to place a ringing-current tone on the line to inform the operator that she is now connected to the operating trunk. It will be noted that relay 234 in every case, 55 upon operating, removes the ground from conductor 278 which is the common source of stop conductor potential for the various connectors. By this arrangement, the supervising switch is given precedence over calls 60 by subscribers so that the operator may be

informed immediately in case of an abnormal condition in the exchange or she may have the right of way in case she desires to call over the operating trunk.

Having operated her ringing key, the operator waits until the call lamp lights, whereupon she operates her answering key and proceeds to dial the digits in the number of the subscribers line in the usual manner. The first eight levels on the connectors are multiple directly to the first eight levels on the supervisory switch, it being assumed that there are not more than eighty lines in the semi-automatic exchange. That being the case, the operator merely dials the first two digits in a number, setting the supervisory switch directly on the desired line. The operator has knowledge of the assigned codes and she operates her special-release key in accordance with the code assigned to the desired subscriber on the called line. Each operation of the special-release key results in an energization of relay 203, Fig. 2. Relay 203 grounds the lower wiper 245 of the supervising switch to afford a return path for the ringing current, and at its upper armature it removes the shunt from ground around the ring back condenser 207 and connects wiper 210 to a source of ringing current through the upper contacts of off-normal relay 231 and through the ninth-level contacts 247. The ringing circuit is taken through normally-open contacts on the off-normal relay 231 so as to prevent an application of ringing current to a connector when the operator is releasing a connector after she has dialled the wrong number, as pointed out hereinbefore. The ninth-level contacts are provided so that no ringing current will be applied when an operator releases a connector seized by the supervisory switch 100 while she is supervising the connectors.

After the operator has obtained the response on the called line and has completed her conversation she releases the supervisory switch by operating her release key in the 105 usual manner.

What is claimed is:

1. In a telephone system, a telephone exchange terminating magneto lines, automatic switching mechanism in said exchange for extending connections from said lines, means responsive to a flow of current from the magneto generator on a calling line for preparing said mechanism to extend the connection from such line, means for thereafter setting up a flow of direct current over said calling line, and means controlled by said flow for maintaining the extended connection. 115

2. In a telephone system, means including automatic switching mechanism in a telephone exchange for extending connections from lines entering said exchange, a source of current on each line, a source of current in the exchange, means responsive to current flow from the current source on a calling 120 line for preparing the automatic switching mechanism to extend the connection from the line, a source of current in the exchange for setting up a flow of current over the calling line, and means controlled by the current in the calling line for maintaining the extended connection. 125

- line for preparing said mechanism for operation to extend said line, means for directively extending the calling line independent of further flow of current from the source on the calling line, and means responsive to current flow over said line from the source at the exchange for maintaining the connection after it is extended. 5
3. In a telephone system, lines terminating at a central exchange, a current source on each line, a current source at the exchange, trunk lines in the exchange, non-numerical switching equipment, means responsive to current flow from the current source on a calling line for operating said non-numerical switching equipment to extend a connection from the calling line to one of said trunk lines, automatic switching equipment in the exchange for extending a connection from the calling line, and means controlled by current flow from the current source at the exchange over the talking line for maintaining the connection after it is extended through said automatic switching mechanism. 15
4. In a telephone system, a plurality of lines entering a central exchange, a current source on each line, a current source at the exchange, automatic directive switches in said exchange, non-numerical switching mechanism in said exchange, means responsive to current flow from the source on a calling line for operating said non-numerical switching mechanism to extend a connection from such calling line to one of said directive switches, means for operating the seized directive switch to extend a connection from the calling line, and means controlled by current flow over the calling line from the source at the exchange for maintaining said automatic switch in its set position after it has been operated. 25
5. In a telephone system in which connections from lines are extended by automatic switching mechanism, lines normally free from connections to active sources of current, means for transmitting an alternating current over any line to the central exchange, means responsive to said alternating current for connecting the line with one of said automatic switches, and a current source associated with the connected automatic switch for producing a current flow over the calling line. 35
6. In a telephone system, subscribers' lines each comprising a pair of talking conductors, each conductor being normally free of potential, a central exchange at which said lines terminate, and means under control of a subscriber on one of said lines and controlled over such line for placing a source of potential on one of the conductors thereof at the central exchange. 45
7. In a party-line telephone system wherein the party lines may be extended by directly-controlled automatic switches in a central office in which the party lines terminate, means including an individual line switch under the control of any subscriber on a party line for connecting his line with a directly-controlled automatic switch in the exchange, and means also under the control of said subscriber for signalling and conversing with other subscribers on the same line without causing such line to be connected with a switch in the central exchange. 55
8. In a telephone system, magneto lines entering a telephone exchange wherein automatic switching equipment is provided for extending connections from calling lines, non-numerical switching equipment for completing connections between said calling lines and automatic switches, means responsive to the operation of a magneto generator on a calling line for operating said non-numerical switching means to connect such line with an automatic switch, means responsive to the subsequent removal of the receiver on the calling station for setting up a holding circuit over the line for maintaining said non-numerical switching means operated, a preliminary holding circuit effective prior to the said removal of the receiver, and means responsive to the subsequent operation of said automatic switch for opening said preliminary holding circuit, leaving the holding of the non-numerical switching mechanism under the control of the calling line. 65
9. In a remote-control semi-automatic telephone-exchange system in which an operating trunk is provided between a semi-automatic exchange and the controlling point, a supervising switch individual to the said operating trunk, and means responsive to an abnormal condition in said semi-automatic exchange for placing said supervising switch under the control of said operating trunk and for signalling the operator at the operating point. 75
10. In a remote-control semi-automatic telephone-exchange system in which an operating trunk is provided between a semi-automatic exchange and a controlling point, a supervising switch individual to the said operating trunk, means responsive to an abnormal condition in said semi-automatic exchange for placing said supervising switch under the control of said operating trunk and for signalling the operator at the controlling point, and means controlled from the operating point for placing said supervisory switch under the control of the operating trunk at the will of the operator at the controlling point. 85
11. In a semi-automatic telephone-exchange system in which the automatic switches in a semi-automatic exchange are remotely controlled from an operating point over an operating trunk, a finder switch individual to said operating trunk and having access to the automatic switches in the semi- 95

automatic exchange, a supervising switch also individual to said operating trunk and accessible to said finder switch, means responsive to a call arriving at one of said 5 automatic switches for operating said finder switch to connect with such automatic switch, and means responsive to an abnormal condition arising in the semi-automatic exchange for operating said finder switch to 10 connect the operating trunk with said supervising switch.

12. In a semi-automatic telephone exchange system in which the automatic switches in a semi-automatic exchange are 15 remotely controlled from an operating point over an operating trunk, a finder switch individual to said operating trunk and having access to the automatic switches in the semi-automatic exchange, a supervising switch 20 also individual to said operating trunk and accessible to said finder switch, means responsive to a call arriving at one of said automatic switches for operating said finder switch to connect with such automatic 25 switch, means responsive to an abnormal condition arising in the semi-automatic exchange for operating said finder switch to connect the operating trunk with said supervising switch, and means for signalling the 30 operator and for placing a distinctive tone on the operating trunk to indicate to the operator that the operating trunk is connected with the supervisory switch.

13. In a remote-control semi-automatic telephone-exchange system wherein an operating trunk connects a semi-automatic exchange with the operating point, a supervising switch controlled over said operating trunk, and means for operating said supervising switch to supervise various portions of equipment in the semi-automatic exchange and for operating said supervising switch to 40 make direct connections between the operating trunk and any one of the lines terminating in the exchange.

14. In a semi-automatic telephone-exchange system of the remote-control type wherein an operating trunk connects the operating point with each remote semi-automatic exchange, terminating equipment at the operating point for each operating trunk, circuit arrangements whereby the operator at the operating point may intermittently interrupt a flow of current over the operating 50 trunk to establish a connection in a semi-automatic exchange, a slow-acting device included in said terminating equipment for interrupting the current flow for sufficient length of time to cause the operating trunk 55 to be disconnected from an extended connection, and operator-controlled means for initiating the operation of said timing means.

15. In a telephone system an operator's switchboard, means for extending a connection to said switchboard and for setting up

a flow of direct current over the trunk line through which the connection is extended, means responsive to a cessation of current flow over said trunk line of a predetermined interval for releasing the extended connection, and a timing device operated at the will of the operator at said switchboard for producing such interruption. 70

16. In a telephone system wherein connections are automatically extended to an operator's switchboard and are subsequently broken by a prolonged cessation of current flow over a control circuit, a slow acting relay at said switchboard, an operator's key, and means responsive to a momentary manipulation of said key by the operator for operating and releasing said slow acting relay to produce the said interruption of current flow in the control circuit. 75

17. In a telephone system in which connections are set up through automatic switching mechanism located at a central exchange, in which the switching mechanism is prepared for operation by current flow from a current source on a calling line, and in which the central-exchange battery has one pole grounded, connections from the poles of the battery to the conductors, respectively, of a prepared calling line, and holding means for maintaining a connection established, said holding means being dependent upon current flow through the connection to the grounded pole of battery and independent of current flow through the other connection to the battery. 80

18. In a telephone system, an automatic switch, means for extending a connection from a subscriber's line to said switch and for maintaining said connection established independent of current flow over said line, means for operating said switch to further 100 extend the connection, and means responsive thereto for rendering the maintenance of the connection between the line and the switch dependent upon current flow over said line. 105

19. In a telephone system, an automatic switch, means for extending a connection from a subscriber's line to said switch and for maintaining said connection established independent of current flow over said line, means for operating said switch to further extend the connection, said switch having a normal position from which it is moved to bring about said extension of the connection, and means responsive to the removal of said switch from its normal position for rendering the maintenance of the connection between the line and the switch dependent upon current flow over the line. 115

20. In a semi-automatic magneto telephone system, an automatic switch in a magneto exchange, means responsive to an application of alternating current to a line entering said exchange for effecting a connection between such line and said switch, a local holding circuit automatically established when the con- 120 125 130

nection is made, means responsive to the subsequent removal of the receiver at a substation on the line for setting up a current flow over said line from the switch, means responsive to said current flow for maintaining the connection, means for signalling the semi-automatic operator when the connection is established, and means controlled by the semi-automatic operator for opening the said local holding circuit.

21. In a semi-automatic magneto telephone system, an automatic switch in a magneto exchange, means responsive to an application of alternating current to a line entering said exchange for extending a connection between such line and said switch, a local holding circuit automatically established when the connection is made, means responsive to the removal of a receiver at a substation on the line for setting up a current flow over said line from the switch, means responsive to said current flow for maintaining the connection, means for signalling the semi-automatic operator when the connection is established, means under the control of the semi-automatic operator for operating said switch to set up a connection from said line to a called line, and means automatically operated incidental to the setting up of the connection for opening said local holding circuit.

22. A trunking combination for a telephone exchange comprising a finder, a plurality of automatic switches directly accessible to said finder, and another automatic switch directly accessible to said finder and having access to the first-named automatic switches.

23. In a semi-automatic telephone system wherein a semi-automatic exchange is remotely operated over an operating trunk from a control point, a finder in said semi-automatic exchange in which said operating trunk terminates, a plurality of automatic switches directly accessible to said finder, another automatic switch directly accessible to said finder and having access to the first named automatic switches, and means for operating said finder independent of control over said operating trunk to connect said operating trunk to any predetermined one of said automatic switches.

24. In a semi-automatic telephone system wherein a semi-automatic exchange is remotely operated over an operating trunk from a control point, a finder in said semi-automatic exchange in which said operating trunk terminates, a plurality of automatic switches directly accessible to said finder, another automatic switch directly accessible to said finder and having access to the first named automatic switches, means for operating said finder independent of control over said operating trunk to connect said operating trunk to any predetermined one of said automatic switches, and means controlled

over the operating trunk for operating said finder to connect with said other automatic switch.

25. A trunking arrangement for automatic exchanges including a finder, a plurality of automatic switches directly accessible to said finder, another automatic switch directly accessible to said finder having access to said first automatic switches, and subscribers' lines directly accessible to all of said automatic switches.

26. In a telephone system wherein connections are set up from calling lines to called lines through automatic directly-controlled switches, a lineswitch terminating a subscriber's line and having access to a plurality of automatic switches, a line relay in said lineswitch having two windings, an operating circuit for one winding including the associated line, a locking circuit for the other winding including locking contacts on the relay, means including other contacts on the relay for operating the lineswitch to select an automatic switch when the line relay is operated over the line winding, and means responsive to the operation of the lineswitch for opening the locking circuit through the other winding of the line relay.

27. In a lineswitch, a line relay having an operating circuit and a locking circuit, an operating magnet having a circuit closed by the line relay, and contacts operated by the operating magnet for opening the locking circuit.

28. In a remote-control semi-automatic telephone-exchange system in which an operating trunk is provided between the semi-automatic exchange and the remote control point, a supervising switch arranged to be controlled by the operator over the control trunk to supervise existing connections, and means responsive to an abnormal condition in said semi-automatic exchange for placing said supervising switch under the control of said operating trunk and for signalling the operator at the operating point.

29. In a semi-automatic exchange wherein the automatic switches are remotely controlled from a remote point over an operating trunk, a supervising switch in the semi-automatic exchange arranged so as to enable the operator to supervise the automatic switches over said operating trunk, said supervising switch being normally disconnected from said operating trunk, and means controlled by an abnormal condition in the semi-automatic exchange for connecting said supervising switch to the operating trunk.

30. In a telephone system wherein a semi-automatic exchange is remotely operated over an operating trunk from a control station, a plurality of automatic switches in said semi-automatic exchange, subscribers' lines accessible to said automatic switches, a supervising switch having access to said automatic

switches and to said subscribers' lines, means for connecting said supervising switch with said operating trunk to place it under the control of the operator at the control station, means in said semi-automatic exchange for initiating the operation of said connecting means, and means at the control station for initiating the operation of said connecting means.

10 31. In a semi-automatic exchange wherein the automatic switches are controlled from a remote station over an operating trunk, a supervising switch in the semi-automatic exchange arranged so as to enable the operator at the control station to supervise the automatic switches over the operating trunk, said supervising switch being normally disconnected from said operating trunk, and means for connecting said supervising switch to said operating trunk.

15 32. In a semi-automatic exchange wherein the automatic switches are controlled from a remote station over an operating trunk, a supervising switch in the semi-automatic exchange arranged so as to enable the operator to supervise the automatic switches over said operating trunk, said supervising switch being normally disconnected from said operating trunk, and means controlled over the operating trunk from the remote station for connecting said supervising switch to said operating trunk.

20 In witness whereof, I hereunto subscribe my name this 29th day of November, A. D. 35 1927.

LEONARD L. RUGGLES.
